UNITED STATES PATENT OFFICE.

JOHN A. LENNARTSON, OF ST. PAUL, MINNESOTA.

CRATE.

Application filed September 29, 1921. Serial No. 504,054.

To all whom it may concern:

Be it known that I, JOHN A. LENNARTSON, a citizen of the United States, residing at St. Paul, county of Ramsey, and State of Minnesota, have invented a new and useful Improvement in Crates, of which the following is a specification.

My invention relates to crates and has for its object to provide a collapsible crate 10 in which all of the parts are connectedly held together in either the erected or collapsed position of the same.

Another object of the invention is to provide a bottom portion having a marginal strip 15 extending around the same within which the top and sides are adapted to be folded when the crate is collapsed, so that the same are contained completely within said marginal strip.

Another object is to form the crate so 20 that no portion thereof projects outside of the bottom and marginal strip when the crate is collapsed so that the crate may be conveniently piled or stacked without obstruction.

Another object is to provide a central partition for holding all of the parts in self-supporting position when the crate is erected.

A still further object is to provide a single latch member for holding the parts properly latched in either the erected or the collapsed position of the crate.

Another object of the invention is to provide 35 a bottom member and a top member together with a number of side members, and to hingedly connect said side members to either of said top or bottom and to slidably connect the other of said side members to the other of said top or bottom.

A still further object is to provide the top of the crate with a central supporting member extending across the entire crate and to provide the top with auxiliary closure members adapted to independently close either of the two compartments formed on each side of the central partition.

The full objects and advantages of my invention will appear in connection with the detailed description thereof and are particularly pointed out in the claims.

In the drawings, illustrating the application of my invention in one form:—

Fig. 1 is a plan view of my invention. 55 Fig. 2 is a sectional elevational view taken on line 2—2 of Figure 1.

Fig. 3 is a sectional elevational view taken on line 3—3 of Figure 1 with the cover member swung open.

Fig. 4 is a view similar to Figure 3 showing the crate partly collapsed.

Fig. 5 is a view similar to Figure 4 showing the crate completely collapsed.

Fig. 6 is a view similar to Figure 3 showing the crate completely collapsed as indicated in Figure 5.

Fig. 7 is an enlarged detail view showing the method of slidably connecting the uprights to the base.

Fig. 8 is an enlarged detail view showing 70 the manner of latching the parts together in the collapsed position of the crate.

My collapsible crate is especially designed for shipping fowls, although it may readily be used for shipping other commodities 75 equally as well.

The device is best shown in Figures 1, 2, and 3 and comprises a base A, a top B, side walls C and D, and end walls E and F. The base A is formed with perimetric strips 80 10, 11, 12 and 13 which are rigidly nailed together at their corners and which have secured to the lower edges thereof a bottom 14 extending completely across the same, having its edges flush with the outwardly 85 extending faces of said strips. For the purpose of stiffening and making it easy to convey the device about the floor a number of skids 15, 16, and 17 are employed which run longitudinally of the crate. The base 90 A forms the container for the walls C, D, E, and F and the top B after the same is collapsed as will be presently explained.

The top B of the device comprises a number of slats 18, 19, 20 and 21 which are securely nailed at their ends to the edges of a pair of battens 22 and 23 which extend downwardly from the said top as clearly indicated in Figure 2. The battens 22 and 23 have hingedly connected to them pairs 95 of uprights 24 and 25 by means of hinges 26 and 27. These uprights have nailed to them cross rails 28, 29, 30 and 31, which form the end walls E and F of the crate proper. To the slat members 18 and 21 are hingedly connected by means of hinges 32, 33, and 34 a number of uprights 35, 36, and 37 similar to the uprights 24 and 25 which in like manner have securely nailed to them rails 38 and 39 forming the side 100 walls C and D of the invention.

It can clearly be seen from Figure 2 that

both the side and end walls are hingedly connected to the top B so that the same cannot be removed therefrom. The method of securing the structure to the base A can best be seen in Figures 2, 3 and 7. Each of the four uprights 24 and 25 is provided with a groove 40 extending along one edge thereof, which groove terminates in a depression 41 formed at the upper end thereof.

5 Within each of the said grooves and depressions is positioned a wire member 42 which is adapted to engage within the depression 41 to hold the said wire member 42 within the uprights 25 and 26. The other end of 10 the wire member 42 is bent outwardly at right angles thereto as indicated at 44 in a manner similar to the end 42 excepting that the same portion extends outwardly in an opposite direction thereto. When member 15 42 is positioned within the slot 40 as before stated, end 43 is engaged within the depression 41 while the body portion of the said wire member lies flush with the edge of the upright and the other end 44 of said wire member projects entirely outwardly beyond said uprights. Throughout 20 the entire length of the two marginal strips 11 and 13 are provided two longitudinal slots 45 and 46.

25 30 These slots are of such a size as to permit the portions 44 of wire members 42 to slide along the same and to permit of the uprights to which said members are connected to swing thereon. To prevent excessive wear of the strips 11 and 13 in the 35 said slots 45 and 46 I provide angular metallic strips 47 which line the upper and outwardly extending surfaces of said slots and strips so as to take up all the wear of said wire members upon the said strips. To prevent the springing inward of the uprights 25 and 24 and the disengagement of the 40 wire members 42 with slots 45 and 46 the said uprights are rabbeted into the lowermost rails 29 and 30 of the end walls E and F as shown in dotted lines in Figure 2.

45 The method of collapsing the device can best be seen in Figures 4 and 5. When the 50 device is erected the parts take the positions as shown in Figures 2 and 3. It will here be noted that the size of the top B including the battens 22 and 23 is such that when the device is collapsed the said top may fold within the strips 10, 11, 12, and 55 13 of the base A. It will be further noted as shown in Figures 1 and 3 that the end walls E and F are of the same width as the top B and exactly fit between the two longitudinal strips 11 and 13. In addition 60 to this the two side walls C and D are formed of a length substantially equal to the distance between the inner portions of the end walls E and F and the battens 22 and 23. This permits of folding both of 65 the side walls C and D upwardly upon the hinges 32, 33, and 34 so that the said walls may take the position indicated in Figure 4. For retaining the said side walls in this position I provide a pair of snap latch buttons 48 such as are now in common use in cabinet work. After the two side walls C and D have been folded up as shown in Figure 4 the same become positioned within and above the two rails 22 and 23 which permit of the swinging of the two end walls E and F upwardly, the said rails 22 and 23 being of such a depth to lie flush with the bottom thereof and to permit the end walls of coming in parallel contact with the side walls after the crate has been completely collapsed as clearly indicated in Figure 5. In this manner it can be readily seen that all of the walls may be folded up relative to the top so that the same all lie in planes parallel to one another positioning all the parts close together so as to avoid waste in space. In collapsing the device the two side walls C and D are first swung upwardly into the position shown in Figure 4 in which position they are held by means of the snap buttons 48. The end walls E and F are now slid inwardly on the wire members 42 along the grooves 45 and 46, which members swing at the hinged connections 27 and 26 after the said sliding occurs. When the said sliding and hinging action is complete the entire structure has taken the position indicated in Figure 5 with the top of the device flush with the top edge of the strip members 10, 11, 12 and 13 extending around the base A, so that no portion of the crate lies above this structure. The action of the device in collapsing is clearly indicated in Figure 4 in which the end wall E is shown as partly moved inwardly and the crate partly collapsed.

50 55 60 65 70 75 80 85 90 95 100 105 110 115 120 125 130

It can readily be seen from the drawings that when the side walls C and D are held outwardly that movement of the end walls E and F is absolutely prevented due to the fact that the edges of the side walls fall within the ends of the end walls so that the same are absolutely held from movement until the said side walls are swung upwardly into the position shown in Figure 4. The device for holding the side walls in position when the crate is erected comprises a central partition which is indicated in its entirety at G. This partition comprises a pair of uprights 50 and 51 which have nailed to them rails 52 and 53. This partition is of a width equal to the distance between the interior portions of the two side walls C and D when the crate is erected and said partition is of a height just equal to the distance between the top B and the bottom 14 to the base A. Partition G is slidably connected in a manner similar to the end walls E and F by wire members identical with the wire

- members 42 positioned in the uprights 50 and 51 so that the said partition is free to slide along the grooves 45 and 46 and to swing upon the ends of these wire members.
- 5 In its erected position partition G is positioned adjacent the uprights 36 of the side walls C and D with its rails 52 and 53 in contact with the edges thereof. When the device is to be collapsed the end wall G is 10 swung about its pivot in the grooves 45 and 46 toward the end wall F until the same lies upon the bottom 14 of the base A. When the same reaches this position the said partition is absolutely free of the 15 two side walls C and D, the said partition lying between the uprights 35 and 36 and below the lowermost rail 39. This permits of swinging the said side walls C and D upwardly to their collapsed position. After 20 the wall members E and F are swung inwardly the extreme end of wall member F engages the upper portion of partition G and as the said wall is slided inwardly said partition is forced along until the same 25 takes the central position as indicated in Figure 5. This movement, however, may be made by hand if desired prior to the collapsing of the end walls. To hold partition G from movement at its lower end 30 when the device is erected I provide a pair of stops 54 in the grooves 45 and 46 which terminate the movement of the lower end of the partition G towards the end wall F. When the upper end of the partition is 35 held from movement by means to be presently described it can be readily comprehended that the said partition is rigidly secured in place.
- For gaining access to the crate I provide 40 a hinged cover member H, which is best shown in Figures 1 and 3. This cover member comprises a pair of slats 55 and 56 which run parallel with the slats 18, 19, 20 and 21 of top B. The said slats have rigidly secured to them battens 57, 58, 59 and 60 which are nailed to the ends and the center portions of said slats and which lie flush with the edge of slat 56 and which project appreciably beyond the edge of the 45 slat 55 to form latch members 61 for holding said cover in place. The cover H is hinged to slat 20 of the top B by means of hinges 62 and 63 of a well known type, which permit of the cover being folded back 50 to lie flush on top of the slats 20 and 21 of top B as clearly indicated in Figure 3 when the cover is thrown open. In opening the cover the same is grasped by the slat 55 and pulled upwardly and towards the side wall D. This swings the cover on the two hinges 62 and 63 in such a manner that the latch portions 61 of slats 57, 58, 59 and 60 are brought away from in under the slat 19. After the said latch portions are freed from 55 slat 19 the cover may be swung upwardly
- on its hinges to take the position indicated in Fig. 3.
- For latching the parts in proper relation I employ a device best shown in Figures 1 and 8. A latch bar 70 is employed which is 70 slidably mounted between the rail 58 and a keeper 71 secured to the two slats 55 and 56. This latch bar is adapted to engage with a latch member 72 secured to the upper rail 52 of the center partition G. At the 75 remote end of the latch 17 the same is turned up at 72 to provide a head for attaching a bolt 73 thereto. Bolt 73 is slidably mounted in a bracket 74 secured to the undersides of slats 55 and 56 and has positioned on 80 it a coil spring 75 co-acting between the head 72 and the bracket 74. When the latch bar 70 is slid along the keeper 71 and bracket 74 against the action of spring 75 the same may be withdrawn from engagement with the latch member 72 to release the partition G. In conjunction with this latching mechanism the battens 58 and 59 are arranged so as to just lie on each side of upper rail member 52 of partition G. It 85 can hence be clearly comprehended that when the latch bar 70 is in engagement with the latch member 72 that the door H is held down in place upon partition G and that partition G is held from movement at 90 its upper portion by means of the battens 58 and 59 and at its lower portion by means of the stop 54 and engagement with the uprights 36. The securing of battens G in this manner holds the side walls C and 95 D from movement when the same are prevented from swinging by the ends of partition G which co-act against the rails 38 and 39 thereof. In a similar manner the said 100 side walls C and D engage the uprights 24 and 25 of the end walls E and F and so hold the same from movement. In this manner the single latch bar 70 holds the entire crate in a rigid erected position. For holding the device latched when collapsed 105 I provide a hinge 77 which is secured on one of its leaves 76 to the bottom 14 of the base A and which has its other hinge 78 adapted to normally lie flat upon the said leaf 76 when the crate is erected and to be swung upwardly in the position shown in Figure 8 when the crate is collapsed so that its extreme end 79 which is formed similar to the latch member 72 may be engaged by 110 the latch bar 70 to hold the parts in fixed position. The keeper 71 may be provided with an upturned lip 80 which together with the hinged member 79 and the latch member 72 may be provided with registering holes 81 through which a seal may be placed 115 to prevent the removal of the contents of the crate and to prevent tampering in any way with the same.
- When the crate is used for shipping fowls I provide a device which may be used in con- 120
- 125
- 130

junction with the door H. This device serves to close either of the two openings to the compartments in the crate when the principal closure member H has been lifted back so that the fowls from either compartment cannot escape while the fowls from the other compartment are being removed. The devices are best shown in Figure 1, each of which comprises a grate shaped wire member 100 which is provided with a number of prongs or tines 101, which are adapted to slide in guide-ways 102 secured to the underside of slat 20. This wire member 100 may be pulled out as indicated in Figure 3 to partially obscure the opening afforded to the particular compartment so that the fowls cannot escape. To prevent the said wire member 100 from being removed from the guide-ways 102 the extreme ends of the tines 101 are bent over as indicated at 103. When the crate is used for other purposes than fowls or animals these devices can be dispensed with.

In the use of my improved crate the same is first erected and the commodity to be shipped packed therein. If desired the latching mechanism may be sealed through the holes 81 of the latching device so that the contents of the crate cannot be tampered with. After the crate has reached its destination and the contents removed the crate may be collapsed as clearly shown in Figure 5 with the latching mechanism positioned as indicated in Figure 8. With the parts as arranged as indicated in Figure 5 the entire construction lies flush with the upper edges of the strips 10, 11, 12, and 13 so that any number of crates may be piled one upon the other without forming an unstable pile. It will be noted that the size of the crates as collapsed is considerably less than when the same are erected thereby effecting a considerable saving of express or freight charges when the crates are returned to the owner. The crate is particularly useful in that the same may be used for any number of purposes without any alteration in the design or arrangement of the parts. One of the principal advantages of the invention lies in the fact that all of the parts are at all times fastened together so that the same cannot be lost and the crate be returned with certain parts thereof missing, thus rendering the same useless. The crate can be erected very rapidly and similarly collapsed with little effort. If desired one of the side doors may be raised upwardly and the crate used for a chicken coop. With the side wall open the crate can be conveniently cleaned and the dirt removed through the opening thus afforded.

In accordance with the patent statutes I have described the principles of operation of my invention together with the apparatus which I now consider to represent the best

embodiment thereof, but I desire to have it understood that the construction shown is only illustrative and that the invention can be carried out by other means and applied to uses other than those above set forth within the scope of the following claims:

I claim:—

1. A collapsible crate comprising a top, a base, end walls hingedly connected to said top, side walls hingedly connected to said top, all of said walls being adapted to be folded beneath said top and positioned between said top and base when the crate is in collapsible position and means for connecting some of said walls to said base. 70 75 80

2. A collapsible crate comprising a base, perimetric strips extending around said base, a top adapted to fit down upon said base, side walls connected to said top, end walls connected to said top, said side and end walls being adapted to be folded beneath said top and to extend within said perimetric strips and beneath said top and base and means for connecting some of said walls to said base. 85 90 95

3. A collapsible crate comprising a top, side walls hingedly connected to said top adapted to fold flat up against the same, end walls hingedly connected to said top adapted to fold flat up against said side walls, a base, means for slidably connecting said end walls to said base, means for holding said parts in erected position. 95

4. A collapsible crate comprising a base, a top, side and end walls adapted to be collapsed within the crate, a partition for holding the parts in erected position, a bolt secured to said top, means formed on said partition and bottom adapted to be engaged by said bolt to hold the crate in collapsed position. 100 105

5. A collapsible crate comprising a base, a top, a partial closure member formed in said top, side and end walls adapted to be collapsed within the crate, a partition for holding the parts in erected position, a bolt secured to said partial closure, means formed on said closure for holding the partition from movement and means formed on said partition adapted to be engaged by said bolt for holding the partial closure closed. 110 115

6. A collapsible crate comprising a base, perimetric strips extending around said base, a top, depending battens secured to said top, walls hinged to said depending battens at one end, and means for slidably connecting said walls at their other end to said perimetric strips. 120

7. A collapsible crate comprising a base, perimetric strips extending around said base, a top, depending battens formed on said top, walls hinged at one end to said battens, and means for slidably and hingedly connecting said walls at their other ends to said perimetric strips. 125 130

8. A collapsible crate comprising a base, perimetric strips extending around said base, a top, depending battens formed on said top, walls hinged at one end to said battens,

5 guide-ways formed in said perimetric strips, and means attached to the lower ends of said walls for pivotally and slidably mounting the lower ends thereof in said guide-ways.

9. A collapsible crate comprising a top, 10 side walls hingedly connected to said top at one end and adapted to swing upwardly to lie flat against the under surface thereof, depending battens secured to said top at the other ends thereof, said battens lying 15 flush with said side walls in their folded up position, and end walls hingedly connected to said battens and adapted to fold up and lie flat against said side walls.

10. A collapsible crate comprising a top, 20 side walls hingedly connected to said top at one end and adapted to swing upwardly to lie flat against the under surface thereof, depending battens secured to said top at the other ends thereof, said battens lying flush 25 with said side walls in their folded up position, end walls hingedly connected to said battens and adapted to fold up and lie flat against said side walls, a base, and means for slidably connecting the lower ends of 30 said end walls to said base.

11. In combination with a collapsible 35 crate having a base comprising a bottom, guide-ways formed along said bottom, walls, grooves formed in said walls, notches formed in the ends of said grooves and a wire member positioned in each of said grooves hav-

ing inwardly turned ends positioned in said notches and outwardly turned ends formed on each of said wire members adapted to engage said guide-ways.

40

12. A collapsible crate comprising a base, a top, end walls movably connected to said base and hingedly connected to said top, stops formed on said base for terminating the movement of said end walls in one direction, side walls hingedly connected to said top and adapted to operate between said end walls, stops formed on said base for terminating the movement of said side wall in one direction, and a partition movably positioned between said side walls for holding the same from movement in the other direction, and means for latching said partition to said top.

45

13. A collapsible crate comprising a base, 50 a top, side and end walls hingedly connected to said top, means for movably connecting some of said walls to said base, a partition positioned between two of said walls and means for slidably and hingedly connecting 55 said partition to said base.

60

14. A collapsible crate comprising a base, a pair of guide-ways extending along the two sides of said base, a top, side and end walls hingedly connected to said top, means 65 for slidably and pivotally securing two of said walls to said guide-ways, a partition positioned within the crate and means for slidably and pivotally connecting said partition to said guide-way.

65

In testimony whereof I affix my signature.
JOHN A. LENNARTSON.

70
